UNITED STATES PATENT OFFICE

AUSTICE A. WISE AND GEORGE GATES, OF OAKLAND, CALIFORNIA

BALL MILL

Application filed May 28, 1928. Serial No. 281,087.

This invention relates to a grinding and amalgamating mill.

More specifically the invention relates to a mill so constructed as to be readily adaptable to the grinding of diverse materials of various forms and sizes, and which may be angularly adjusted in accordance with the requirements of materials of differing characteristics.

10 Various forms of mills including the ball type have long been in vogue for the grinding of different materials in which the material is fed into a revolving drum disposed horizontally or at various angles to a horizontal in which the material is subjected to a grinding action within the drum.

The importance of having the revolving drum inclined to a horizontal has long been recognized but in such prior constructions the revolving drum had a fixed inclination. In the grinding of different materials it is desirable that the drum be given different inclinations according to the characteristics of the material it is desired to grind.

25 A primary object of the invention is to provide a ball mill, for grinding ores or for any other purpose, that is bodily adjustable so that its axis of rotation may assume various angles with respect to a horizontal line.

30 A further object of the invention is to provide a ball mill that is supported at three points whereby the angular adjustment of the mill may be effected by adjusting the relative position of two of said points, so that a stable support is provided for the mill in all positions of its adjustment.

A further object of the present invention is to provide a grinding mill comprising a 40 revolving drum disposed at an inclination and adapted to be readily shifted to other inclinations without interfering with the drive connections.

45 A further object of the invention is to provide a grinding mill adapted to be expeditiously adjusted for the grinding of different materials.

50 A further object of the present invention is to provide a grinding mill adapted to be readily adjusted for increasing or decreas-

ing the capacity thereof in accordance with the material desired to be handled.

A further object of the present invention is to provide a ball grinding mill composed of simple detachable parts whereby any broken or worn parts may be readily replaced at minimum expense.

A further object of the present invention is to provide a grinding mill in which the bearings and driving mechanism are housed, thus preventing the entrance of dirt or any abrading or destructive material thereto.

In the treatment of ores bearing precious metals such as gold, it has been the practice to grind the ore by various forms of mills and thereafter subject the ground ore to an amalgamating process in order to recover the gold, etc. thus involving separate steps and operations in such treatment.

It is a still further object of the present invention to provide a combined grinding and amalgamating mill whereby ores bearing precious metals may be ground and the values recovered in a single operation.

With the foregoing objects in view as well as others that may appear from the following detailed disclosure, reference will be had to the accompanying drawings forming a part thereof, and in which:

Figure 1 is a part longitudinal section and part side elevation of a preferred embodiment of our invention.

Figure 2 is an end elevation as viewed from the plane of line 2—2 in Figure 1 with half the grate removed, and

Figure 3 is a similar view as viewed from the plane of line 3—3 in Figure 1.

Referring to the drawings by reference characters in which like characters designate like parts, 11 designates a foundation preferably of concrete and which, as clearly shown in Figure 1, is provided with parallel inclined supporting portions 12 and 13.

Disposed on supporting portion 12 is a metallic plate 14 to which is secured the bases of transversely extending I-beams 15 which as shown in Figure 1 are laterally spaced apart and supports on the outer faces thereof, a longitudinally slotted metallic plate 16.

Adjustably supported on plate 16 as by

means of bolts 17 extending through slots therein are two pairs of dust-proof and grease tight ball bearings 18 and 19 each of which pairs revolvably supports a trunnion 21 to which is secured a roller 22. Revolvably supported on rollers 22 is a cylindrical casing 23 provided with a track 24 in bearing engagement with rollers 22.

Casing 23 is provided with a flanged end 10 plate 25 which carries a hub member 26 to which is secured one end of drive shaft 27.

Supported on supporting portion 13 of foundation 11, is a plate 28 provided with an outwardly extending limiting flange 29.

15 Supported on plate 28 with one edge thereof in limiting engagement with flange 29 is a plate 31 provided with a spherical seat 32 in which movably rests the spherical shell 33 of the main combination thrust ball bearing 34 in which shaft 27 is journalled.

20 Fixed on the outer end of shaft 27 is the hub 35 of a worm gear 36 which is in mesh with a worm 37 fixed to a shaft 38 extending at right angles to shaft 27, shaft 38 on opposite ends of worm 37 is journalled in combination thrust ball bearings 39 which are supported by plates 41 movable within arcuate slots 42 in guide castings 43 secured together and to foundation 11 by means of transversely 25 extending securing bolts 44.

25 Supported by bearings 39 and surrounding worm gear 36 and worm 37 is a metallic casing 45 provided with an upper removable section 46 and through which hub 35 of gear 36 extends as shown in Figure 1.

30 Casing 23 is welded on a horizontal seam and has one end thereof slipped within the flange of end plate 25 whereupon said flange is welded to casing 23.

35 Disposed within the shell 23 in engagement with end plate 25 is a head liner 47 which may be formed in a single piece or several segments and which is secured in position by means of the adjacent section of 40 a plurality of successive circular liners 48 as well as being secured to shaft 27.

45 Circular liners 48 are placed in casing 23 in succession with adjacent edges in engagement as shown in Figure 1, which jointly provide a continuous liner for casing 23.

50 Disposed within casing 23 and in engagement with the outer liner section 48 is an annular grate 49 which holds liners 48 all in position within casing 23. Grate 49 may be made in one or more sections and formed with openings 51 of a size depending upon the product to be ground, and the height of the grate is also dependent upon the product to be ground. The grate is so formed that 55 the portion which abuts adjacent liner section 48 is of the same thickness as clearly shown in Figure 1, so that no shoulder is formed adjacent the grate.

55 Disposed in engagement with grate 49 is an annular screen 52 of a mesh depending

upon the material to be ground. As clearly shown in Figure 1, grate 49 is provided with extensions 53 in order that screen 52 will be out of contact with the operative portion of grate 49 in order to more efficiently perform 70 its screening operation.

As indicated in Figure 1, casing 23 at the forward or open end thereof is turned outwardly, extending for a short distance and then turned inwardly to provide a channel or trap 54. Telescoped within the open end of casing 23 is a cylindrical amalgamating plate 55 one end of which engages screen 52 to hold the same in position against grate 49 and the other end of which is provided with 80 a flange 56 extending within trap 54.

85 Welded to casing 23 adjacent trap 54 is a cast steel angle ring 57 through which and flange 56 bolts are extended to hold liner sections, grate, screen and amalgamating plate 85 all in operative position.

90 A feed chute 58 is provided which is preferably in the form of three quarters of a circle in cross section as indicated in Figure 2 and which enters the open end of casing 23 90 high enough to clear grate 49 and extends well back within the casing.

95 The interior of casing 23 with liners 47 and 48 in position is filled with balls 59 to a level indicated by line 61 and the casing 23 with associated parts is set into rotation by suitable power transmitted to pulley 62 secured to shaft 38.

100 In the operation of the construction disclosed, the ore or other material to be treated is fed through chute 58 into casing 23 well toward the rear end thereof which casing is constantly and uniformly revolved through any source of power transmitted to pulley 62 and through shaft 38, worm 37, gear 36, and shaft 27 which is fixed to casing 23.

105 The ore is discharged from chute 58 into contact with balls 59 which due to rotation of casing 23 are in constant motion and, accordingly, the ore is subjected to a crushing and grinding action between balls 59 and liners 47 and 48. The ore is fed with a stream of water and as the ore becomes ground or pulverized the finer material will work forward and pass through grate 49 and screen 52, on 110 to amalgamating plate 55 and be discharged over the edge thereof into trap 54 and thence be discharged out of the mouth or open end of mill or casing 23.

115 The amalgamating plate 55 being directly in front of screen 52, the ground ore passing through grate 49 and screen 52 moves directly on to the amalgamating surface. The amalgamating plate is constantly rotating in unison with casing 23 and grate 49 and screen 52 which keeps the milled product agitated and by the rotary motion of the amalgamating plate same will continually present a new surface and due to the up-grade of milled product the tendency is to retard the waste of 120 125 130

gold or amalgamation by wash of the milled product.

In view of the constant rotation of the amalgamating plate 55 while the water is flowing from the mill through screen carrying the milled product with it as the casing rotates, causes the gold to readily cling to the amalgam surface.

After the milled ore has been retained on the plate long enough to be turned over many times it moves off and drops into trap 54.

The amalgam trap 54 will collect quick silver, gold and other losses which leaves plate 55 if any and the outer lip of trap 54 may be raised a little higher than the level of amalgamating plate 55 depending upon the ore and the operator's judgment as there should be but very little of the values pass over the outer lip of trap 54.

The amalgamating plate 55 is preferably composed of a silvered copper plate or plates and as the ground material passes thereover and free gold contained therein will be attracted by the amalgamating plate as just stated. Said plate, after a certain period of operation, is removed and the amalgam distilled in well known manner to recover the gold.

If it is desired to change the pitch or incline of casing 23 for the most effective treatment of various materials, the operator loosens bolts 17 and moves bearings 18 and 19 along plate 16 toward or away from each other depending upon whether a greater or less pitch is desired and as bearings 18 and 19 are moved, rollers 22 are moved therewith and consequently casing 23, the track 24 of which rides on rollers 22, is correspondingly changed in pitch or inclination.

As the pitch of casing 23 is altered, shaft 27 moves therewith remaining at all times in alinement with the longitudinal axis of casing 23, such movement of shaft 27 being permitted through the co-operating spherical seat 32 and spherical bearing shell 33, gear 36 and worm 37 remaining in operative engagement during any pitch alternations of casing 23 and shaft 27, due to bearings 39 for shaft 38 being carried by plates 41 movable in an arc whose center corresponds with that of the spherical engaging surfaces 32 and 33, it being only necessary in such adjustments to tighten or loosen the belt co-operating with pulley 62.

It will be seen that the mill comprising casing 23 and shaft 27 has a three point suspension which insures self alinement thus avoiding any danger of strain in any of the operating parts and that bearing 34 sustains a large portion of the weight of the mill as well as the end thrust and further serves as a fulcrum in the pitch adjustments of the mill.

It is to be further noted that gear 36 and worm 37 are self contained and housed against destructive matter and due to their

arcuately movable connection with foundation 11 permit a perfect alinement drive at any pitch of casing 23 and shaft 27.

From the foregoing disclosure, it will be seen that the entire structure is composed of relatively few and simple parts which are protected against destructive agents and yet are readily accessible for removal or repairs and that the structure is admirably adapted to the purpose for which it is intended.

Worm 37 may be readily removed without disturbing gear 36 by the simple operation of removing one of the end plates 41; and as the liner for casing 23 is formed of a plurality of sections any one thereof may be removed and replaced without the necessity of providing a complete new liner.

While the structure is disclosed for the grinding of ores and collecting metals such as gold therefrom by the process of amalgamation, the mill is well adapted for grinding any product either wet or dry. When used as a dry grinder, for products such as paints and other earthen substances, the grate 49 and screen 52 may be moved forward as amalgamating plate 55 will not be required and furthermore such forward movement of grate 49 and screen 52 will provide greater capacity of casing 23. Also where soft, earthen products are to be milled the casing 23 may be set on most any pitch or incline which would have a tendency to increase or decrease the capacity as the operator may choose, and the change in pitch will not affect the mechanical drive as same is a flexible three point suspension and the parts are positively in alinement at all times.

For grinding a material, the product of which is a light flower dust or a gas, it would be necessary to close the mouth or open end of casing 23 in which event the material would be fed through the center of casing 23 by means of a suitable worm or scoop feed and a discharge opening would be provided for the ground product.

While we have disclosed but a single embodiment of our invention, it is to be understood that we are not limited to the details thereof but may make such changes or alterations as fairly fall within the scope of the subjoined claims.

Accordingly, what we claim and desire to secure by United States Letters Patent is:—

1. A grinding mill comprising a base; rollers supported on said base; a rotatable casing supported on said rollers; a drive shaft carried by said casing; a movable connection between said shaft and said base; driving means carried by said shaft; said casing and said shaft supported on said base in an inclined position; and means for changing the inclination of said casing and said shaft.

2. The construction defined in claim 1 in which said movable connection comprises a spherical seat in said base and a co-operating

spherical ball and thrust bearing carried by said shaft.

3. The construction defined in claim 1 in which said last means comprises bearings for said rollers and means for adjusting said bearings relative to each other.

4. The construction defined in claim 1 in which said driving means comprises a worm gear secured to said shaft; a worm meshing with said gear; said worm and worm gear being adjustable as a unit.

5. A grinding mill comprising a foundation; substantially parallel inclined seats on said foundation; adjustable rollers supported on one of said seats; a spherical socket on the other of said seats; a cylindrical casing rotatably supported on said rollers; a drive shaft supported by said casing; a ball and thrust bearing for said drive shaft; said bearing provided with a spherical surface for operative engagement with said socket; and driving means co-operating with said shaft.

6. In the construction defined in claim 5, a slotted plate carried by said one of said seats; bearings supported on said plate; shafts rotatably supported in said bearings, said rollers being secured upon said shafts; and means for adjusting said bearings relative to said plate.

7. The construction defined in claim 5 in which said driving means are movably supported by said foundation.

8. A grinding mill comprising a foundation; a cylindrical inclined rotatable casing supported by said foundation; a drive shaft carried by said casing; a ball and socket joint between said shaft and said foundation; a worm gear fixed to said shaft; a worm meshing with said gear; a casing surrounding said gear and said worm; means for altering the inclination of said casing; and means whereby said casing surrounding said gear and said worm moves commensurate with any such change in inclination.

In testimony whereof we affix our signatures.

AUSTICE A. WISE.
GEORGE GATES.
